UNITED STATES PATENT OFFICE.

ALBERT STREICHER, OF NEW YORK, N. Y.

SHELL-TIMING DEVICE.

Application filed January 12, 1923. Serial No. 612,166.

To all whom it may concern:

Be it known that I, ALBERT STREICHER, a citizen of the United States, residing at New York, in the county of New York and State of New York, have invented certain new and useful Improvements in Shell-Timing Devices, of which the following is a specification.

This invention relates to a device for setting the caps on ordnance shells which are used to determine the point at which the shell will explode, these caps being set to different explosion points by rotation on the shell body.

The present invention has for a general object to provide a novel and improved device of this kind which can be readily manipulated in the dark.

For further comprehension of the invention, and of the objects and advantages thereof, reference will be had to the following description and accompanying drawings, and to the appended claims in which the various novel features of the invention are more particularly set forth.

Fig. 1 of the drawings is a side view of my improved device showing it in place on a shell.

Fig. 2 is a front view of the device.

Fig. 3 is a longitudinal sectional view of the device, also showing it in position on a shell.

Fig. 4 is a rear view of the device.

Fig. 5 is a fragmentary longitudinal sectional view showing a modified form of position finder.

Fig. 6 is a fragmentary rear view of the plate used in this modified construction.

Referring now to the drawings, my improved device comprises a ring 10 having a handle 11 fixed to one side thereof and projecting in a common plane therewith. The inner wall of this ring is checked out at one side to receive a plate 14 in which is a comparatively large central aperture 15 having its wall flattened on opposite sides as at 16. The plate 14 may be fixed in the ring 10 by means of the screws 17. Upon the opposite face of the ring 10 to that in which the plate 15 is set, is an inturned flange 20 and in the space between said flange and the plate is positioned for free rotary movement, a flat ring 22, from the rear face of which a substantially semi-cylindrical flange 23 projects this flange being of a diameter to fit snugly over the fore-part of the shell body, indi-

cated at 24. This flange 23 may be knurled or roughened on its outer face as indicated at 23' to facilitate gripping.

It is by relative rotation of the two rings 10 and 22 one on the other that the cap is set for explosion of the shell at the proper point, this being accomplished by the following means. Formed on the ring 10 adjacent the handle 11 is a radially inwardly projecting lug 26 which projects over the rear face of the flat ring 22 and over a dovetail annular groove 27 formed in said rear face. In this groove 27 is freely set a short block 28 of complementary cross section to the groove and which may be locked in the desired adjusted position by means of a screw 29 threaded through the block and adapted to engage in any one of a number of sockets 27' formed in the bottom wall of the groove, this screw having a handle extension 29' formed thereon whereby it may be turned. Fixed at one point in the groove 27 is a stud 32 which projects rearward from the face of the ring 22 and is adapted to engage the lug 26 to limit the relative movement of the two rings in one direction, for the purpose to be presently made apparent.

Formed on and projecting forwardly from the plate 14 are several bosses 35, as here shown three, which are hollow, presenting passages extending completely therethrough and also through the said plate. In these bosses are slidably positioned pins such as 36 each having a cap 37 fixed to its outer end to provide a depressing knob or button whereby it may be moved inward to engage shallow depressions in the forward face of ring 22 and which are arranged in three arcuate rows numbered respectively 37', 38 and 39. Each pin is normally held away from the face of the ring by an expansion spring 40 coiled therearound and bearing against a flange 41 on the pin, outward movement of the latter being limited by the bearing of the flange against a suitable shoulder in the boss 35.

The depressions of the inner row 37' are arranged at considerably different arcuate spacing from that of the two outer rows, so that the two rings will have a greater rotary movement on one another to bring successive depressions into registry with the corresponding pin on the plate 14, the depressions 37' being spaced at such distances as represent rotary movement of the cap corresponding to main subdivisions of the

distance elements or time elements determining the explosion of the shell. As here indicated the depressions 37' are so arranged that when the cap is turned on the shell 5 through an arc corresponding to the spacing thereof the shell will explode at one thousand metres distance, while the depressions of the intermediate row 38 are arranged to represent hundred metre distances and those 10 of the outer row 39 equal subdivisions thereof.

These parts just described are intended for use in the dark, the setting being done, when light is available, by means of markings 43 on the ring 22 viewed through an opening 44 in the outer ring 10.

The operation of the device, when no light is available is as follows: The two rings 10 and 22 are first rotated on one another until the stud 32 abuts against the lug 26 as shown in Fig. 4, which is the zero point of the device. The two rings are then given a relative rotation on one another to move the stud away from the lug and the pins 36 25 over the depressions in the plate 14. During this movement one finger of the user is held pressing against the pin adapted to register with the inner row 37' of depressions, if the firing distance is over one thousand metres.

30 Assuming say, a distance of two thousand one hundred and fifty metres, the rotary movement of the rings is continued until the pin engages in the second of these depressions. The finger is then removed from 35 the pin and placed on the pin which registers with the intermediate row of depressions 28 and the rings moved further until this pin registers with the first succeeding depression. The finger is then removed 40 from this pin and placed on the outer one and the rings moved further until this pin registers with the first succeeding depression. The total relative angular movement which the two rings have been given during 45 the above described operation represents the degree of rotation which must be given the cap on the shell to fire at the proper point. The block 28 is then moved along the groove until it engages the other side 50 of the lug to that which had been engaged by the stud at the zero point of the device, and is locked in this position by turning the screw whose end enters into one of the sockets 27' which will be understood to have 55 a suitable spacing for this purpose. The setting of the cap is then accomplished by placing the device on the end of the shell with the flange 23 fitting against the body of the shell and the plate 14 engaging the 60 cap, indicated at 24', the latter being formed with flat sides corresponding to the flattened parts of the opening 15 in the plate. The shell and the flange are gripped in one hand and the handle 11 in the other, the ring 10 65 and plate 14 being rotated on the shell

through the limits allowed by the stud 32 and block 28 and correspondingly moving the cap.

In the modified construction shown in Figs. 5 and 6 I have shown, instead of the series of pins 36 on the plate 14, a single lever 50 extending vertically with respect to the plate 14 and forwardly therefrom, this lever being fulcrumed between its ends as at 51 on an ear 52 on the plate and projecting at its rear end through a slot 52 in the plate and into a circular or part-circular groove 54 in the forward face of the ring 22. In the opposite walls of this groove are curved notches or depressions 55 and 56 80 respectively having a general spacing corresponding to the depressions 37' and 38 or such other spacing as may be desirable. The lever 50 is normally held in neutral position in the groove 54 by means of a pair of springs 58 which are secured at one end to the ear and bear at their opposite ends on opposite sides of the lever. In the operation of this form of the device the finger of the user pulls the lever first into engagement with one wall of groove 54 and then in engagement with the other wall, thereby determining the proper setting.

Having thus described my invention what I claim as new and desire to protect by Letters Patent of the United States is as follows:

1. A device of the class described comprising a pair of rings adapted for limited rotation on one another, one of said rings being formed with circumferentially spaced indentations, an element on the other ring adapted to yieldingly engage in said indentations, and means for limiting the relative rotary movement of said rings between 100 points determined by the engagement of the said element in a selected one of the said indentations.

2. A device of the class described comprising a pair of rings adapted for limited rotation on one another, one of said rings being formed with circumferentially spaced indentations, an element on the other ring adapted to yieldingly engage in said indentations, and means for limiting the relative rotary movement of said rings between 110 points determined by the engagement of the said element in a selected one of the said indentations, said means comprising a fixed lug on the last named ring, and fixed and movable stop members on the first named ring.

3. A device of the class described comprising a pair of rings adapted for limited rotation on one another, one of said rings being formed with circumferentially spaced indentations, an element on the other ring adapted to yieldingly engage in said indentations, and means for limiting the relative rotary movement of said rings between 125 130

- points determined by the engagement of the said element in a selected one of the said indentations, said means comprising a fixed lug on the last named ring, and fixed 5 and movable stop members on the first named ring, said movable stop member comprising a block slidable in a circular groove in the first named ring, and having a screw threaded therethrough for locking it to the 10 said ring.
4. A device of the class described comprising a pair of rings adapted for limited rotation on one another, one of said rings being formed with circumferentially spaced 15 indentations, an element on the other ring adapted to yieldingly engage in said indentations, and means for limiting the relative rotary movement of said rings between points determined by the engagement of the 20 said element in a selected one of the said indentations, said means comprising a fixed lug on the last named ring, and fixed and movable stop members on the first named ring, said movable stop member comprising 25 a block slidable in a circular groove in the first named ring, and having a screw threaded therethrough for locking it to the said ring, said ring having a circularly arranged series of sockets in which the end of said 30 screw is adapted to engage.
5. A device of the class described comprising a pair of rings arranged for limited rotation on one another, one of said rings being formed with two arcuate rows of indentations, a device on the other ring adapted to yieldingly engage in the indentations 35
- of either row, and means for limiting the relative rotary movement of said rings between points determined by the engagement of the said device on a selected one of the 40 said indentations.
6. A device of the class described comprising a pair of rings arranged for limited rotation on one another, one of said rings being formed with two arcuate rows of indentations, a device on the other ring adapted to yieldingly engage in the indentations of either row, and means for limiting the relative rotary movement of said rings between points determined by the engagement 45 of the said device on a selected one of the said indentations, said device comprising a lever pivoted between its ends on the said last named ring.
7. A device of the class described comprising a pair of rings arranged for limited rotation on one another, one of said rings being formed with two arcuate rows of indentations, a device on the other ring adapted to yieldingly engage in the indentations 50 of either row, and means for limiting the relative rotary movement of said rings between points determined by the engagement of the said device on a selected one of the said indentations, said device comprising a lever pivoted between its ends on the said last named ring.
- In testimony whereof I have affixed my signature.

ALBERT STREICHER.
